US0D1006205S

(12) **United States Design Patent** (10) **Patent No.:** **US D1,006,205 S**
(45) **Date of Patent:** **** Nov. 28, 2023**

(54) **AIR FILTER SUPPORT**

(71) Applicant: **Therma-Stor LLC**, Madison, WI (US)

(72) Inventors: **David Treleven**, Raleigh, NC (US); **Robert John Motiff**, Columbus, WI (US); **Todd R. DeMonte**, Cottage Grove, WI (US); **Jenee LaPlace Mobley**, Fuquay Varina, NC (US); **Kevin Lawrence Askling**, Madison, WI (US)

(73) Assignee: **THERMA-STOR LLC**, Madison, WI (US)

(**) Term: **15 Years**

(21) Appl. No.: **29/805,306**

(22) Filed: **Aug. 26, 2021**

(51) **LOC (14) Cl.** **23-04**

(52) **U.S. Cl.**

CLAIM

The ornamental design for an air filter support, as shown and described.

DESCRIPTION

FIG. 1 is a front top left perspective view of one embodiment of the device;

FIG. 2 is a front top right perspective view of one embodiment of the device;

FIG. 3 is a front bottom left perspective view of one embodiment of the device;

FIG. 4 is a front bottom right perspective view of one embodiment of the device;

FIG. 5 is a rear top left perspective view of one embodiment of the device;

FIG. 6 is a rear top right perspective view of one embodiment of the device;

FIG. 7 is a rear bottom left perspective view of one embodiment of the device;

FIG. 8 is a rear bottom right perspective view of one embodiment of the device;

FIG. 9 is a front view of one embodiment of the device;

FIG. 10 is a back view of one embodiment of the device;

FIG. 11 is a left side view of one embodiment of the device;

FIG. 12 is a right side view of one embodiment of the device;

(Continued)

FIG. 13 is a top view of one embodiment of the device; and, FIG. 14 is a bottom view of one embodiment of the device.
